LUGGAGE CASE OR SIMILAR ARTICLE

Samuel J. Holtzman, 8201 Symphony Drive,
Baltimore, Md.

Continuation of design applications Ser. No. 65,287 and
Ser. No. 65,288, May 23, 1961. This application
Oct. 3, 1962, Ser. No. 72,044

Term of patent 14 years

(Cl. D87—5)

FIG.1

FIG.2

FIG. 3

FIG. 4

FIG. 1 is a perspective view of a luggage case or similar article embodying my new design wherein the panel is recessed with respect to the adjoining wall portion of the molded cases;

FIG. 2 is a vertical cross-sectional view taken approximately in the plane of line 2—2 of FIG. 1;

FIG. 3 is a perspective view of another embodiment of my new design wherein the panel is raised with respect to the adjoining wall portion of the molded case; and

FIG. 4 is a vertical cross-sectional view taken approximately in the plane of line 4—4 of FIG. 3.

The essential feature of my design resides in the full line portions and more particularly in the panel located intermediate the ends of the case and continuing from the top face around the longitudinal edges of the case into the front and rear faces thereof, and being divided

transversely across the top by the parting line of the case substantially as shown.

This application is a continuation of my pending applications Serial No. D-65,287, filed May 23, 1961, and Serial No. D-65,288, filed May 23, 1961, both of which are now abandoned.

I claim:

The ornamental design for a luggage case or similar article, as shown and described.
